UNITED STATES PATENT OFFICE.

LINN B. ABBOTT, OF BRIDGEPORT, CONNECTICUT.

GROUND-CLAMP.

1,123,060.

Specification of Letters Patent. Patented Dec. 29, 1914.

Application filed July 25, 1911. Serial No. 640,510.

To all whom it may concern:

Be it known that I, LINN B. ABBOTT, a citizen of the United States, residing at Bridgeport, in the county of Fairfield and State of Connecticut, have invented a new and useful Ground-Clamp, of which the following is a specification.

My invention relates to improvements in clamps for attaching electric wires to pipes, etc., for the purpose of grounding said electric wires.

The objects of my improvements are: First, to provide a clamp which may be quickly and easily applied without the removal of nuts or bolts which are frequently dropped or lost. Second; to provide means of securing various sizes of wire without the use of solder. Third; to provide a clamp without projecting screws or nuts which are likely to become caught and damaged. Fourth; to provide means of easy adjustment to overcome variation in size of pipes and wires.

With these and other objects in view, which will be readily apparent to those skilled in the art, my invention consists of the novel construction, combination and arrangement of parts hereinafter more fully described, illustrated and claimed.

While susceptible to embodiment in various ways by the use of different mechanical equivalents, my invention is well exemplified by the form shown in the accompanying drawings, in which;

Figure I is a side view of my clamp as applied to a pipe and shows the manner of holding the wire therein.

Fig. II is a vertical section taken through C—D in Fig. I looking in the direction of the arrows.

Fig. III is an end view of my clamp before being applied to the pipe. This shows one arrangement of the flexible clamping strap 3, i. e. the two ends of the strap being over the tightening slide and the central portion of the strap bearing upon the pipe. This same arrangement is perhaps more clearly shown in Fig. II.

Fig. IV is a top view of the tightening slide 2. This shows the tapped hole 9 through which the tightening screw 4 acts. It also shows the slots 10 which guide the movement of this part in the rectangular openings, 11^a and 11^b in part 1. These

slots also act to prevent the spreading 55 apart of the supporting member 1, when the pressure of the screw is applied.

Fig. V is an end view of the flexible clamping strap 3 showing another arrangement of the same, i. e. the central portion 60 as well as the two ends being over the tightening slide. This is the preferred form although the two ends may be folded outside the central portion with equally good results.

Fig. VI is an end view of the flexible clamping strap 3, showing still another arrangement of the same, i. e. the central portion of the strap only being over the tightening slide, the two ends arranged to only 70 85 partially encircle the pipe.

Fig. VII is a view of the supporting part 1, shown in perspective. This shows the central hole 7 through which the screw 4 passes freely, the adjacent metal supporting 75 the head of the screw. The rectangular openings 11^a and 11^b receive the tightening slide and coöperate with the slots 10 in guiding its movement. The bottom of this supporting part is curved as at 12^a and 12^b 80 to more nearly fit the curvature of the pipe.

Fig. VIII is a bottom view of the flexible clamping strap 3. This shows the hole 8 through which the tightening screw passes. This hole may be both in the middle of the 85 strap and in both ends, as shown in Fig. V. Or it may be only in the ends of the strap as arranged in Figs. II and III. Or it may be only in the central portion of the strap as arranged in Fig. VI. This 90 figure also shows the loops 14 and the spaces 13 which are formed at the bottom of the flexible strap. These loops 14 interlap through the intervening spaces 13 and form a tubelike opening in which the wire 95 6 is inserted.

The action of the clamp is as follows: The clamp is first placed upon the pipe, the curved portion of the supporting part 12^a and 12^b resting against the pipe and a leg 100 of the flexible strap on each side of the pipe. The ends of these legs are then brought together and the ground wire is inserted in the tubelike opening formed by the interlapping of the loops in the ends of 105 the strap. The screw is then tightened, this raises the tightening slide which in turn raises the top of the flexible strap,

tending to separate the interlapping loops. This action tightens the loops upon the wire and binds it firmly to the pipe.

Having thus described my invention what I claim as new is:

1. A device of the class described, comprising a flexible strap, a supporting member having guiding openings therein, a movable member having slots therein, the portion adjacent to said slots aiding to support said supporting member and a screw for moving said movable member.

2. In a device of the class described, in combination, a band encircling a pipe, the two extremities of said band being held from separation by a wire, and suitable means for tightening said strap to hold said wire in position.

In testimony whereof I have hereunto set my hand this 29th day of July, 1911.

LINN B. ABBOTT.
